UNITED STATES PATENT OFFICE.

JONAS JAMES PIERCE, JR., OF BUFFALO, NEW YORK.

METAL RAILWAY-TIE.

No. 922,626.

Specification of Letters Patent.

Patented May 25, 1909.

Application filed June 15, 1908. Serial No. 438,496.

To all whom it may concern:

Be it known that I, JONAS JAMES PIERCE, Jr., a citizen of the United States, residing at Buffalo, in the county of Erie and State of New York, have invented a new and useful Improvement in Metal Railway-Ties, of which the following is a specification.

This invention relates to a metallic railway tie and has the object to produce a tie of plate or sheet steel or other metal which possesses the maximum strength, rail seating and ballast engaging area for the amount of metal used, which is sufficiently resilient to furnish an elastic support for the load running over the same and which is incapable of being displaced either vertically or laterally in the road bed.

In the accompanying drawings: Figure 1 is a perspective view of my improved metallic tie showing a rail secured upon one end of the same. Fig. 2 is a fragmentary vertical longitudinal section of the same. Fig. 3 is a vertical transverse section in line 3—3, Fig. 2. Fig. 4 is a plan view of the blank from which the tie is made.

Similar letters of reference indicate corresponding parts throughout the several views.

The tie as an entirety has the form of an inverted trough and consists generally of a horizontal top A, two vertical side walls or legs B, B extending downwardly from opposite longitudinal edges of the top and horizontal base flanges C, C extending laterally from the lower edges of the side walls. The central part a of the top is contracted into a double wedge form or made narrower than the end portions a' thereof, whereby the tie when embedded in ballast is anchored and prevented from moving laterally relatively to the road bed. The side walls of the tie follow the contour of the top and are of uniform height throughout their length. Each base flange however is wide at its central part c and narrow at its end parts c' and has a straight outer longitudinal edge c". A tie of this construction may be formed from a rectangular blank of sheet or plate steel by pressing the same between the die and punch of a "bull dozer" or press. In thus forming the tie from a rectangular plate the metal which is omitted from the central part of the top of the tie to narrow the same is retained and provides the increased width of the central parts of the flanges. By this means the blank can be employed in the rectangular form in which it leaves the mill and readily

converted into a tie having the central parts of its top and side walls contracted while the central parts of its flanges are increased in width, thereby obtaining the maximum bearing surface or area in the flanges and utilizing all the metal in the blank to the best advantage. The cost of the tie is materially reduced inasmuch as special rolling or preparation of the blank is unnecessary; no trimming of the tie after being shaped is required and no metal is wasted as scrap for this purpose. The bearing surface of the same may be increased by providing the same in line with the rail supporting points with shoes D having the form of flat plates which extend across the underside of the base flanges and are secured thereto by turning the opposite ends d upwardly against the outer edges of the flanges and inwardly and downwardly against the upper side of the same, as shown in Figs. 1 and 3.

If desired, the space within the tie may be filled with ballast, concrete or other suitable material which may be introduced through the open ends of the tie and through an opening e formed centrally in top of the same.

The rails F rest with their base flanges in seats G formed in the top of the tie by depressing this part of the same sufficiently to form shoulders g, g on opposite sides of the seat which engage with the opposite edges of the rail base and confine the same against lateral movement on the tie. The rails may be secured to the tie by any suitable means, those shown for this purpose in the drawings consisting of washers or clip plates h arranged partly on the tie top and partly on the rail base and bolts i connecting the washers with the tie top, as shown in Figs. 1 and 2. By providing depressed seats on the tie for the rails the shoulders of the seats relieve the strain on the fastening bolts and prevent the same from being sheared off.

For the purpose of increasing the bearing area of the rails on the tie the side walls of the same are bulged or deflected outwardly in line with each seat, as shown at J, whereby the area of the seat is increased in the direction of the length of the rail and a more extensive and efficient support for the same is provided. The metal for thus increasing the area of the rail seats is derived partly from that which is displaced in depressing the rail seat in the top of the tie, whereby this displaced metal is used to advantage in increasing the bearing area of the tie without in-

creasing the weight of the same. By thus increasing the area of the rail seats on the tie, the number of ties usually required for a certain length of track may be reduced, thereby effecting a saving in cost of installing a railway.

My improved railway tie is very light and strong, it absolutely prevents the rails from spreading and owing to the narrow center no lateral movement of the same in the road bed is possible. The natural resiliency of the material from which it is made and its form of construction allow the rails to move under rapid movement of the load on the same and also minimizes crushing of the ballast as occurs to a large extent in ties of solid construction. Height of vertical legs, width of flanges, depth and width of depression for rail base, length of tie and width of face can be readily changed to suit varying conditions of the road bed, traffic and rail section, by changing the size of the rectangular plate and using different dies in shaping.

I claim as my invention:

25 1. A railway tie pressed from a plate of metal and having a horizontal top which is narrow at the center and wide at opposite ends, vertical side walls connected at their upper edges with opposite longitudinal edges of the top and following the contour of the same and base flanges projecting laterally from the lower edges of the side walls those parts of the side walls which are transversely in line with the narrow part of the top being of the same thickness as the ends of the walls which are transversely in line with the wide parts of said top.

40 2. A railway tie pressed from a rectangular plate of metal and having a horizontal top which is narrow at the center and wide at opposite ends, vertical side walls connected at their upper edges with opposite longitudinal edges of the top and following the contour of the same, and base flanges projecting laterally from the lower edges of the side walls

and each having a wide central part and narrow parts at opposite ends those parts of the side walls which are transversely in line with the narrow part of the top being of the same thickness as the ends of the walls which are transversely in line with the wide parts of said top.

3. A railway tie pressed from a rectangular plate of metal and having a horizontal top which is narrow at the center and wide at opposite ends, vertical side walls connected at their upper edges with opposite longitudinal edges of the top and following the contour of the same, and base flanges projecting laterally from the lower edges of the side walls and each having a wide central part, narrow parts at opposite ends and a straight outer longitudinal edge those parts of the side walls which are transversely in line with the narrow part of the top being of the same thickness as the ends of the walls which are transversely in line with the wide parts of said top.

4. A railway tie pressed from a plate of metal and having a horizontal top, upright side walls connecting at their upper edges with opposite longitudinal edges of the top, and outward deflections in said walls in line with the place where the rails rest on the top of the tie.

5. A railway tie pressed from a plate of metal and having a horizontal top, upright side walls connecting at their upper edges with opposite longitudinal edges of the top, the top of the tie having seats depressed therein for supporting the rails and the side walls of the same being bulged or deflected outwardly in line with said depressed seats for increasing the bearing area of the latter.

Witness my hand this 27th day of May, 1908.

JONAS JAMES PIERCE, JR.
